UNITED STATES PATENT OFFICE.

ALFRED W. G. WILSON, OF OTTAWA, ONTARIO, CANADA.

BALL FOR SHRAPNEL AND METHOD OF MAKING THE SAME.

1,246,204.

Specification of Letters Patent. Patented Nov. 13, 1917.

Application filed May 19, 1915. Serial No. 29,249.

To all whom it may concern:

Be it known that I, ALFRED WILLIAM GUNNING WILSON, a citizen of the Dominion of Canada and a British subject, residing at Ottawa, in the county of Carleton and Province of Ontario, Canada, have invented new and useful Improvements in Balls for Shrapnel and Methods of Making the Same, of which the following is a specification.

My invention relates to a process for producing balls which are designed for use in shrapnel shells or for use wherever such balls are required. Whereas balls which are employed for this purpose must possess sufficient rigidity to prevent their being flattened at the time of discharge of their container or carrier, and whereas the desired rigidity is now obtained by using an alloy of metals, usually of the metals lead and antimony, the object of my invention is to obtain the desired rigidity in a ball of essentially the same characteristics in all other respects by providing an internal core of one metal or alloy, of as high a specific gravity as may be necessary and by covering this core with an external sheathing or shell of another metal or alloy possessing different physical properties. This external sheathing or shell completely surrounds the internal core before mentioned, and is in intimate contact with it at all points, the combination of internal core and external shell producing a solid metallic ball of the desired rigidity and weight. For example, one type of ball made by this process of my invention will consist of a solid core of the metal lead and a sufficiently rigid external sheathing or shell of steel, the latter more or less completely surrounding the internal core and being in intimate contact with it at all points, the combination of the internal core of one material which possesses a high specific gravity with the external shell of a different material which possesses other physical properties which render a thin hollow spherical shell of this material sufficiently rigid for the purpose intended, producing a solid metallic ball of the size and weight required, and possessing the rigidity necessary for the purpose for which it is required.

The invention is illustrated in the accompanying drawings in which Figure 1 shows a disk from which the outer covering of the ball is made. Figs. 2 and 3 show the disk

after being subjected to forming and shaping operations. Fig. 4 shows a core in place in the covering of Fig. 3. Fig. 5 shows the covering or cup being closed around the core, and Fig. 6 shows the latter operation completed.

I attain the object of my invention in the manner indicated below and illustrated in the accompanying drawings. I cut a disk, shown at Fig. 1, of the proper size, from a sheet of metal or alloy selected as suitable for forming the external sheathing or covering of this type of ball. I subject this disk to a succession of forming and shaping operations, by employing suitable dies and plungers, producing eventually a hemispherical cup with a short cylindrical portion attached, shown in section at Fig. 3; the requisite quantity of the metal or alloy which is to form the solid core of the ball is then inserted in this cup by any suitable means; Fig. 4 is a section showing the core material at "a" in place in the bottom of a cup "b" made of the sheathing metal; the open top of the cylindrical portion of the cup, as shown in section at "b" in Fig. 4, is then drawn and partially closed by means of proper dies to produce the form shown in section in Fig. 5 "b"; and finally the cup is closed more or less completely, producing a solid metallic ball, as shown in section in Fig. 6. In producing balls of this type by my process it is not essential that the core material be introduced into a cup made of the sheathing material at the stage of the process illustrated in Fig. 3; it may be inserted at an earlier stage in the process of forming the spherical sheathing shell from the disk of sheathing material, as shown at Fig. 2, or it may be introduced at some later stage, as when the form shown in Fig. 5 "b" has been reached, or it may be introduced when the sheath has been formed into a spherical shape with only a very small opening at one point; the time of introduction of the core material is not an essential feature in the operation of my process, and can be varied at will to suit the convenience of the operator, without in any way departing from the employment of the essential features of my process for producing solid metallic balls.

I am aware that prior to my invention balls consisting of a core of one metal or alloy and an external sheathing of another metal or alloy have been produced for use

in small arms ammunition, the said balls, or bullets, having a cylindrical or conical form, but I verily believe that the process described herewith has never been employed for the purpose of making balls for use in shrapnel shells, and I do not claim the invention of a bullet formed by means of the combination of an external sheathing or shell and an internal core of a different material, broadly.

It will be noted that the compression of the soft metal core by the shell during the formation will increase the density of the internal core, increasing its rigidity and enabling a greater weight to be concentrated in a small space.

I claim—

1. A ball for shrapnel and the like com-

prising a soft metal core and a casing of hard metal completely inclosing the core 20 and compressing the same.

2. A ball for shrapnel and the like comprising a completely spherical casing of steel, a lead core contained therein and compressed thereby. 25

3. The hereinafter described method of manufacturing balls for shrapnel and the like which consists in forming a cup from a disk of relatively hard metal then placing a soft metal core therein and then compressing the casing to completely inclose the soft metal core contained therein. 30

ALFRED W. G. WILSON.
